UNITED STATES PATENT OFFICE.

FREDERICK G. JAHN, OF NEW YORK, N. Y., ASSIGNOR TO THE INTERNATIONAL POSTAL SUPPLY COMPANY OF NEW YORK, OF BROOKLYN, NEW YORK, A CORPORATION OF NEW YORK.

RHEOSTAT.

No. 861,365.

Specification of Letters Patent.

Patented July 30, 1907.

Application filed December 8, 1904. Serial No. 235,914.

To all whom it may concern:

Be it known that I, FREDERICK G. JAHN, a citizen of the United States, residing at borough of Brooklyn, city of New York, county of Kings, and State of New York, have invented certain new and useful Improvements in Rheostats, of which the following is a specification.

The present invention relates to rheostats such for instance as those commonly known as motor starters 10 and as speed controllers, and in this case capable of use as either or for both.

It has for its object to generally improve and simplify the construction and mode of operation of the rheostat and to increase its general efficiency and reliability to the end that it will instantly and automatically respond to any excessive load on the motor due for instance to the clogging of the machinery it drives, to an excess in current passing to the motor or to an increase in the current beyond the safety 20 point due to too suddenly closing the circuit. And it furthermore has for its object to provide means by which the motor may be effectively stopped through the instrumentality of the rheostat mechanism, instead of depending as heretofore on an independent 25 circuit breaking or line switch.

The improved construction in its preferred form consists of a movable circuit closing arm arranged to close the circuit between a single "live" contact and either one of a plurality of independent contacts with 30 interposed resistance coils and to break the circuit when resting against a "dead" piece or pieces. Between the single "live" contact and the "line" there is interposed an automatic circuit breaker, which circuit is otherwise normally closed, and which consists, 35 preferably, of a pair of separable contacts and a solenoid magnet, the movable core of which, should for instance an excess of current or too high a rise in amperage occur, will be forcibly propelled through the magnet to separate or move one of the separable contacts away from the other to break the circuit and thus 40 instantaneously relieve the motor of any increase of current beyond the point of safety. This automatic breaking of the circuit compels the return of the circuit closing arm to its "dead" or initial position and 45 this return movement is made the means of returning the separable contacts into correct relation with each other, so that when said arm is again and not too suddenly moved the circuit through the arm to the motor will be maintained until another occasion for the 50 automatic circuit breaking action arises. The separable contacts and the circuit closing arm are furthermore made the means, when the motor is to be stopped, for breaking the circuit through the instrumentality of said arm at its initial return movement 55 and immediately before it leaves the final independ-

ent contact to pass on to the next preceding contact, so that all sparking between the surfaces of the arm and the independent contacts is prevented and its use as a means of stopping the motor as well as for starting it, is rendered feasible and practical. With 60 this general understanding of the improvement a detailed description of a practical embodiment thereof will now be given, reference being had to the accompanying drawings, in which:

Figure 1, is a front elevation. Fig. 2, is a vertical 65 cross section on the line 2, 2, of Fig. 1. Fig. 3, is a rear elevation. Fig. 4, is an elevation of the automatic circuit breaker showing the parts in their moved or circuit breaking position. Fig. 5, is a detail sectional elevation of the circuit closing arm and its 70 immediate parts. Fig. 6, is a sectional detail of a modification taken on the plane of the supporting plate looking from the rear; and Fig. 7, is a sectional side elevation of the same. Fig. 8, is a diagram of the circuits through the rheostat and motor. 75

The parts of the improved rheostat are supported by a single stone slab or other suitable plate B, arranged for attachment in the position for use. The front or exposed face of the plate supports independent electric contacts or segments 10, 11, 12, 13 and 14, a long 80 electric contact or segment 15, diametrically opposed to said five independent segments and two diametrically opposed "dead" contacts or segments D, D¹; the whole being grouped in circular form around a common horizontal axis. With these segments there 85 contacts a movable circuit closing arm 16, centrally mounted at said axis and having at each of its free ends bearing faces for surface contact with the several segments and to make contact between diametrically opposed portions of the circular arrangement of segments. 90 On the rear of the supporting plate B, four resistance coils between the five electric contacts or segments are preferably provided by two resistance pieces C, C¹, each piece carrying two independent portions of the resistance, supported by cast iron cores 40—41 with 95 suitable insulation.

The circuit closing arm 16, is centrally carried on a horizontal oscillatory rod 17, that is mounted to turn in a comparatively long hub-like bearing 18, secured to the supporting plate B, through its outer head or 100 flange 19. The circuit closing arm and horizontal rod 17, are moved by a hand-lever 20, secured to the outer end of the rod and is arranged to move more or less freely and remain in any position to which it may be moved between two limiting stops 21, 22, the lever 105 abutting faces of which are covered with soft rubber or other noise deadening substance. The circuit closing arm 16, is loose on the horizontal rod, and connection between it and the hand lever is had by a stud 23, Fig.—5, of fiber or other insulating material carried on 110

the rear of the lever and entering a recess in the front face of the arm, and a washer 24, of similar material is interposed between the arm and hand-lever around the rod 17. The rear end of the horizontal rod 17, has 5 fast to it an arm 25, forming an abutment for a fiber or similar disk 26, loose on the rod and between which and the rear of the supporting plate and encircling the rod is a coiled spring 27, the action of which tends to constantly pull the circuit closing arm into firm 10 surface contact with the surface of the circular arrangement of segments. The washer 24, between the contact arm and hand-lever has one surface convexed to fit a concaved seat in the face of the arm 16, Fig—2, and at the same time interpose a bushing between the 15 arm and the rod and thus thoroughly insulate the arm from the rod and from the hand-lever and at the same time providing a joint adapting the contact arm to adjust itself in surface bearing contact with the segments independent of the proper alinement of the 20 horizontal rod or the proper surface adjustment of the contact or segments. The spring 27, also serves to hold the circuit closing arm and hand-lever together and with sufficient frictional contact against the segments to allow said arm and lever to remain in whatever 25 position they may be moved without danger of jar affecting such position.

At or near the limit of the circuit closing movement of the arm 16, there is arranged a contact piece or post 38, having a yielding spring-pressed pin 39, see Fig. 1, 30 in electric connection with the binding post F, Figs. 3 & 8, against which post or its yielding pin the end of the arm will bear as soon as it moves to fully close the circuit with the last independent contact 14, so that the current which would otherwise have to pass 35 through all the resistances to the post F, will be short circuited through the arm and contact piece 38, to said post F.

The electric circuit is held normally closed between the source of electric energy or line and the long segment 40 15, but is rendered breakable by an automatic circuit breaking device E, consisting of a so called knife-switch and a solenoid magnet 34. In this instance the switch consists of a rocking contact finger 30, coating with a pair of spring contact blades 31, the 45 finger being pivotally mounted to a post 32, and having a weighted end 29, to facilitate its breaking movement, and the spring contact blades are secured fast to a post 33, both posts extending from the rear of the supporting plate. The movable finger is held in circuit 50 closing position by the friction thereon of the spring contact blades, it being otherwise free to move by reason of its weighted end.

The contact finger 30, is positively moved between the spring blades by a fiber or similar pin 28, fixed 55 to the arm 25, of the horizontal rod 17, which arm and pin are so arranged with respect to the circuit closing arm and hand-lever that when the arm is in its initial position resting against the two "dead" segments D, D¹, and the hand-lever is against the "off" 60 limiting stop 21, the separable contacts 30 and 31, will be in electric contact and the circuit will be closed between the source of electric energy or line and the long segment 15, while the continuity of said circuit to the motor will be broken by the "dead" position 65 of the circuit closing arm 16, as in Figs—1, 2 and 3.

The solenoid magnet 34, included in said circuit to the separable contacts 30, 31, is of the usual form having the downwardly extended shell secured in a bearing 35, fast to the rear of the supporting plate B, thus holding the magnet axially immediately below the 70 rocking contact finger 30, of the separable contacts. The magnet core 36, movable through the center of the magnet, has at its upper end a fiber or similar button 2, for striking and moving the movable finger 30. The down or normal position of the core 36, in the magnet is determined by an adjustable screw 37, threaded into the bearing 35, its head forming a seat for the end of the core, as in Fig—2. The position of this core will be adjusted to allow a stated normal current to pass through the magnet and thence to the motor 75 without energizing said magnet sufficient to move the core. But after the circuit closing arm had been moved to close the circuit to the motor and has thereby removed the pin 28, from position immediately above the movable finger 30, should the current exceed the 80 normal safety amperage the magnet will be instantly energized and the core forcibly drawn upwardly therein to move the contact finger 30, from the spring blades 31, and thus break the circuit to the motor, as indicated in Fig—4. When this occurs the hand-lever will be 85 moved to return the circuit closing arm back to its "dead" or initial position thereby through the movement of the pin 28, returning the contact finger 30, into contact with the spring blades 31, as in Fig—3.

As before stated the automatic breaking of the 90 circuit may be made to occur from any one of the several causes enumerated and the improved rheostat may be made or adjusted to care for any one or all of such occasions.

Where the current is heavier say than two or three 100 amperes it is desirous in order to prevent sparking and the consequent burning of the independent contacts and circuit closing arm 16, to wholly break the circuit to the motor. In the present instance, see Figs—6 and 7, the circuit closing arm and the separable 105 contacts of the automatic circuit breaker are made the instrumentalities by which this may be effected, thereby providing a single accessible device for stopping as well as starting the motor. The contact finger 30, is fast to one end of its pivot spindle 46, the other 110 end carrying a short arm 3, projecting into the path of movement of a spring seated stud 4, carried in a projection from the circuit closing arm 16. When the said arm 16, is moved to the final independent contact 14, in starting the motor the stud 4, yields idly 115 past the short arm 3, but when it is desired to stop the motor immediately the circuit closing arm 16, is started in its return movement in the direction of the arrow Fig—6, and before its bearing surface wholly leaves said contact 14, and touches the next preceding contact 13, the stud 4, will have struck and so far moved the short arm 3, as to have rocked the contact finger 30, away from the spring blades 31, to break the circuit to the motor. As the circuit closing arm is returned to its initial "dead" position, 125 the pin 28, will have acted to return the contact finger 30, to its current closing position.

From what has been described the electric circuits through the improved rheostat will be rendered clear from an examination of the diagram Fig—8. It 130

simply remains to be set forth that the line *a* connects with the binding post *L*, thence through the coils of the solenoid magnet 34, through the separable contacts 31 and 30, to the single long segment 15. The 5 current then passes by the circuit closing arm 16, when it is moved from its "dead" position to the first independent contact 10, through the resistances *C*, *C*¹, and other independent contacts 11 to 14, and from said last contact to the binding post *A*, thence to one 10 of the brushes of the motor *M*, through its armature and the other brush to the line *b*. A portion of the current passes from the initial independent contact 10, through the posts 38 and *F*, to the field of the motor, and as the circuit closing arm moves over the contacts 15 to the last one this portion of the circuit passes through the successive resistances to the motor field, successively growing weaker as the current to the motor armature grows stronger, until the arm finally rests on said last contact 14, and the whole strength of the 20 current passes to the armature. At this time, however, a short circuit is formed between the end of the circuit closing arm and the contact piece 38, making the circuit from the arm to the binding post *F*, and thence through the motor field and one of the brushes 25 to the line *b*, so that the current to the field need not traverse the resistances.

From the foregoing it will be understood that the improved structure as a whole provides a rheostat of exceeding simplicity and wherein the mechanical 30 members and the wiring and connections may be viewed at a glance so that any difficulty in its proper working will be immediately detected and easily remedied. Its availability is also enhanced in that the necessity for a wholly separable and independent 35 circuit breaker or line switch is avoided.

What is claimed is:

1. A resistance circuit including a circuit closer coöperating successively with the resistances therein, and manually operated in both directions, separable contacts independent of said circuit closer and its contacts and a magnet adapted when energized by a rise in the current to separate said separable contacts by the direct impact of its 40 armature.

2. A resistance circuit including a circuit closer coöperating successively with the resistances therein, and manually operated in both directions, separable contacts independent of said circuit closer and its contacts, a magnet adapted when energized by a rise in the current to separate said separable contacts by the direct impact of its 45 armature and means operated by the circuit closer to restore the separable contacts.

3. A resistance circuit including a circuit closer coöperating successively with the resistances therein, separable contacts and means connected with the circuit closer for first 50 separating said contacts in the initial movement of said circuit closer to its "off" position and then restoring said contacts on its arrival at said position.

4. A resistance circuit including a circuit closer coöperating successively with the resistances therein, separable 55 contacts, means connected with the circuit closer for first separating said contacts in the initial movement of said circuit closer to its "off" position and then restoring said contacts on its arrival at said position and a magnet for automatically separating the contacts on a rise in the current.

65

5. A resistance circuit including a circuit closer coöperating successively with the resistances therein, separable contacts, means for automatically separating said separable contacts on a rise in current and means connected with the circuit closer for separating the separable contacts. 70

6. The combination of a resistance circuit, an independent circuit breaker including a magnet to automatically operate the same, and a circuit closer coöperating with both and manually operated in both directions to both make and break the circuit. 75

7. The combination of two pairs of independent separable contacts in a circuit and a single instrumentality manually operated in both directions with means coöperating with both pair of contacts to independently close and break the circuit with each pair. 80

8. A resistance circuit including a circuit closing arm, a pair of independent separable contacts separable to break the circuit independent of the movement of the closing arm and means carried by said arm for separating said contacts. 85

9. A resistance circuit including a circuit closing arm, manually operated in both directions, an independent pair of separable contacts, means movable with said arm in closing the circuit through the resistances to insure also the closing of the circuit through said separable contacts, 90 means for automatically breaking the circuit through said separable contacts and on the reverse movement of said arm to break the circuit through the separable contacts.

10. A resistance circuit including a circuit closer therefor manually operated in both directions and having an insulated projection carried therewith, and an automatic circuit breaking mechanism the movable contact of which is idly mounted and adapted to be moved in one direction by the direct push of said mechanism and in the other direction by the direct act of the circuit closer and projection. 95

11. An axially supported circuit closing arm, an insulating bushing between said arm and its axial support and a spring for frictionally holding the arm, bushing and support together. 100

12. A circuit closing arm loosely mounted on a rock-shaft an interposed insulating ball bearing bushing, a hand-lever fast to said shaft and having insulated connection with said arm and a spring for holding the arm and bushing frictionally together. 105

13. A rheostat consisting of a supporting plate having on its front face resistance and line contacts, a circuit closing arm supported in bearings in the plate and coöperating with said contacts, and said plate having on its rear face the resistance coils, a pair of separable contacts coupled by the act of said arm and also a magnet adapted on a rise in current to separate said contacts by the direct impact of its armature. 115

14. A rheostat consisting of a circular arrangement of contacts, a two armed lever coöperating therewith, separable contacts coupled in the act of moving the lever in one direction and a magnet the armature of which is adapted to contact with and separate the separable contacts on a rise in the current. 120

15. A rheostat consisting of a circular arrangement of contacts, a two armed lever coöperating therewith, separable contacts separated in the initial movement of said lever in the "off" direction and restored as its final act in arriving at the "off" position. 125

In testimony whereof, I have signed my name to this 130 specification in the presence of two subscribing witnesses, this 7th day of December 1904.

FREDERICK G. JAHN.
